US00D603000S

(12) **United States Design Patent**
Garcia

(10) **Patent No.:** **US D603,000 S**
(45) **Date of Patent:** **** Oct. 27, 2009**

(54) **TOY**

D544,812 S * 6/2007 Limber D11/129

(75) Inventor: **Jesus Garcia**, Alhambra, CA (US)

* cited by examiner

(73) Assignee: **Republic Import Company, Inc.**,
Commerce, CA (US)

Primary Examiner—T. Chase Nelson
Assistant Examiner—Zenia I Bennett

(**) Term: **14 Years**

(74) *Attorney, Agent, or Firm*—Christina S. Loza; Loza & Loza, LLP

(21) Appl. No.: **29/334,909**

CLAIM

(22) Filed: **Apr. 3, 2009**

The ornamental design for a toy, as shown and described.

(51) **LOC (9) Cl.** **21-01**

DESCRIPTION

(52) **U.S. Cl.** **D21/638; D21/468**

FIG. 1 is a perspective view of a toy in a collapsed configuration, showing my new design;

(58) **Field of Classification Search** D21/468,
D21/621, 622, 623, 625, 627, 629, 638, 645–649;
446/268, 305, 360–361, 376, 379, 328, 384;
D6/595, 596, 597, 599, 601, 604; D11/128,
D11/129

FIG. 2 is a perspective view showing the toy in an extended configuration;

See application file for complete search history.

FIG. 3 is a front elevational view of the toy in a collapsed configuration;
